DESIGN FOR A DISPLAY FRAME

Charles A. Van Evera, Berkeley, Calif., assignor
to Standard Stations, Inc., San Francisco,
Calif., a corporation of Delaware

Application June 23, 1933. Serial No. 48,514

Term of patent 14 years

To all whom it may concern:

Be it known that I, CHARLES A. VAN EVERA, a citizen of the United States, residing in the city of Berkeley, county of Alameda, State of California, have invented a new, original, and ornamental Design for a Display Frame, of which the following is a specification, reference being had to the accompanying drawing, forming part thereof.

In the drawing:

Fig. 1 is a front elevation and
Fig. 2 is a top plan view of a display frame
showing my new design.

I claim:

The ornamental design for a display frame, as shown.

Signed at San Francisco, California, the 8th day of June, 1933.

CHARLES A. VAN EVERA.
